US00D819681S

(12) **United States Design Patent** (10) Patent No.: **US D819,681 S**
(45) Date of Patent: **** Jun. 5, 2018**

(54) **DISPLAY SCREEN WITH GRAPHICAL USER INTERFACE**

(71) Applicant: **Google Inc.**, Mountain View, CA (US)

(72) Inventors: **Simon Fung**, Mountain View, CA (US);
Thomas Homer Rutledge, San Jose, CA (US);
Jongmin Kim, San Jose, CA (US); **Raj Krishnan**, New York, NY (US)

(73) Assignee: **Google LLC**, Mountain View, CA (US)

(**) Term: **15 Years**

(21) Appl. No.: **29/591,228**

(22) Filed: **Jan. 18, 2017**

(51) LOC (11) Cl. **14-04**

(52) U.S. Cl.

USPC **D14/487**

(58) **Field of Classification Search**

USPC D14/485-495
CPC ... G06F 3/04817; G06F 3/0481; G06T 13/80;
G06T 15/02; H04N 1/00424

(57) **CLAIM**

The ornamental design for a display screen with graphical user interface, as shown and described.

DESCRIPTION

The FIGURE is a view of a display screen with graphical user interface, showing our new design.

The broken lines of uneven length show the display screen and form no part of the claimed design. The broken lines of even length shown in the drawing illustrate portions of the display screen with graphical user interface that form no part of the claimed design.

1 Claim, 1 Drawing Sheet
